UNITED STATES PATENT OFFICE

FRED A. CONRAD, OF MILWAUKEE, WISCONSIN, ASSIGNOR TO AMERICAN LACE PAPER COMPANY, OF MILWAUKEE, WISCONSIN, A CORPORATION OF WISCONSIN

DESIGN FOR A PAPER DOILY

Application filed March 16, 1931. Serial No. 39,099. Term of patent 14 years.

To whom it may concern:

Be it known that I, FRED A. CONRAD, a citizen of the United States, residing at Milwaukee, in the county of Milwaukee and State of Wisconsin, have invented a new, original, and ornamental Design for Paper Doilies, of which the following is a specification, reference being had to the accompanying drawing, forming part thereof.

The drawing is a plan view of a doily embodying the invention wherein the detailed illustration shows the two principal component units of the design with reference to each other, duplicates of said units about the doily being illustrated in dotted lines.

I claim:

The ornamental design for a paper doily as shown and described.

FRED A. CONRAD.
